UNITED STATES PATENT OFFICE.

JAMES E. TODD, OF PHILADELPHIA, PENNSYLVANIA.

POTATO-CUTTER.

1,320,294.

Specification of Letters Patent. Patented Oct. 28, 1919.

Application filed May 13, 1919. Serial No. 296,738.

To all whom it may concern:

Be it known that I, JAMES E. TODD, a citizen of the United States, residing at Frankford, Philadelphia, in the county of 5 Philadelphia and State of Pennsylvania, have invented new and useful Improvements in Potato-Cutters, of which the following is a specification.

This invention relates to a device for cutting vegetables such as potatoes and the like and the principal object of the invention is to provide means for forcing the vegetables against a plurality of knives for cutting the same into small pieces.

Another object of the invention is to provide means for adjusting the knives to regulate the size of the pieces in which the potato is cut and also to provide several sets of knives whereby the potato may be cut 20 into slices or into small pieces.

Still another object of the invention is to provide means whereby large vegetables will have portions cut therefrom so that the remaining part will fit the apparatus.

The invention also consists in certain other features of construction and in the combination and arrangement of the several parts, to be hereinafter fully described, illustrated in the accompanying drawings 30 and specifically pointed out in the appended claims.

In describing my invention in detail, reference will be had to the accompanying drawings wherein like characters denote like 35 or corresponding parts throughout the several views, and in which:—

Figure 1 is a sectional view of the invention;

Fig. 2 is a plan view;

Fig. 3 is a front view of one of the knife frames;

Fig. 4 is a like view with one frame placed in front of the other;

Fig. 5 is a top view of one of the frames 45 with the slide omitted;

Fig. 6 is a view of a modification.

In these views 1 indicates a casing which is of substantially rectangular form with its top open and a hopper 2 is placed on said top 50 or is formed thereon by extending the sides of the case upwardly. The rear end of the case is also open and guides 3 are formed on the side walls at this opening. These guides 55 are adapted to receive the knife frames 4 and 5. Within the case is located a plun-

ger 6, the rod 7 of which passes through the front wall of the case. This rod is provided with a guide 8 which receives the lower end of an operating lever 9 which is pivoted to the braces 10 projecting outwardly from the front of the case. The guide 8 is formed of a cross piece 11 carried by the bolts 12 projecting from the outer end of the rod 7, and the rollers 13 which are journaled on said bolts between the rod 7 and the cross piece 8. These rollers engage the lever 9 and thus reduce the friction between the parts when the device is operated.

At the bottom of the hopper at the rear thereof is located a knife 14 and above the knife is located a plate 15 which is pivoted intermediate its ends, as at 16, to the hopper. A spring 17 holds the lower end of the plate in a position directly over the edge of the knife. A stop 18 limits the movement of this plate by the spring. As will be seen, the knife 14 is located above the path of movement of the upper edge of the plunger so that if a potato would be so large as to have a portion projecting above the upper edge of the plunger, this knife 14 would cut the same and the plate 15 would give to permit the cut portion to pass over the top of the knife. When the parts are withdrawn the spring would cause the plate 85 to return the upper portion of the potato to the hopper.

Each of the knife frames is of substantially rectangular form with one side provided with the slots 19 and the opposite side 90 with notches 19' to receive the knives 20. After the knives are placed in position with their ends engaging these slots the slide 21 is placed in position over the open end of the frame to hold the knives against displacement. This slide engages the grooves 19' formed in the slotted side of the frame. By this means the knives may be adjusted as to their distance apart so as to cut strips of different sizes.

When the potatoes are to be cut into strips only one knife frame is used, but when the potatoes are to be cut into small pieces both frames are used with the knives in one frame extending at right angles to those in the other frame.

The case is provided with an arm 22 at its lower end carrying a thumb nut 23 by which the device may be attached to a table or other support.

100

110

As shown in Fig 6, I may operate the plunger by means of a gear wheel 22' engaging a rack 23' formed on the plunger rod 7', the wheel being turned by the crank 5 handle 24.

What I claim is:-

1. A device of the class described comprising a case, a reciprocating plunger therein, means for reciprocating the plunger, cutting means carried by the case, a hopper connected with the case above the plunger, a knife at the rear end of the hopper above the path of the plunger, a pivoted plate within the hopper having its lower end adjacent the cutting edge of the plate and

spring means for holding the plate in vertical position.

2. A knife holding frame for potato cutters comprising a rectangular frame having notches formed in one of its inner walls 20 and slots passing through the opposing wall, said slots and notches being spaced apart, said slotted wall having grooves therein, knives having their ends engaging said slots and notches and a slide engaging 25 said grooves for removably holding the knives in place.

In testimony whereof I affix my signature.

JAMES E. TODD.
